METHOD OF MANUFACTURING CLOSED
LINK BRAKE HANGERS

Frederic Schaefer, Pittsburgh, Pa.

Application July 6, 1931. Serial No. 548,829

5 Claims. (Cl. 29—164)

This invention relates to the manufacture of closed link or loop brake hangers for supporting the brake beams on railway car trucks, the object being to improve the method of manufacturing such brake hangers disclosed in my Patent No. 1,716,933 and in my allowed application, Serial No. 445,899 filed April 21, 1930, to the end that the resulting hangers will have greater strength and uniform dimension at the intersections of their horizontal yokes and vertical legs, and that the flow lines will emerge at a point where complex stresses do not occur.

The invention is illustrated in the accompanying drawings, of which Fig. 1 is a perspective view of a metal bar of cylindrical cross section from which a closed link hanger is forged; Fig. 2 is a plan view of a hanger blank forged from the bar of Fig. 1, the blank being shown in full lines as being engaged by expanding tools, and in dotted lines after being expanded; Fig. 3 is a plan view of the finished hanger; Fig. 4 is a detail sectional view taken on the line IV—IV of Fig. 3; Fig. 5 is a similar view taken on the line V—V of Fig. 3; and Fig. 6 is a plan view of a modified form of hanger blank which may be forged from the bar of Fig. 1, the blank being shown in full lines as being engaged by expanding tools, and in dotted lines after being expanded.

In the actual manufacture a brake hangers according to the methods of my said patent and application, an elongate rolled steel bar is first forged to form a brake hanger blank having at least two sides parallel, and then two of such sides are engaged by an expanding tool and spread apart until a rectangular link is formed. However, with either of these methods a certain amount of distortion of the metal occurs at the intersections of the yoke and leg-forming portions of the blank when it is expanded to final rectangular form, because these intersections, all of which are at obtuse or acute angles, must produce the right angle corners of the finished hanger. Therefore, the distortion and resulting weakening has taken place in the corners of the hanger which are the points where a hanger is subjected to maximum stresses, the loads being there transmitted from the horizontal yokes to the vertical legs by combined tension and bending stresses.

In accordance with my invention, a rectangular closed link brake hanger having parallel opposite-disposed yokes and legs is formed by first forging from a unidirectional rolled steel bar of suitable cross section an elongate hanger blank having spaced substantially parallel sides con-

nected by looped ends, each of the sides including two substantially right angle intersections of the yoke-forming and leg-forming portions of the blank, the metal at these intersections being in the same form as in the finished hanger. 60 Thereafter, each side of the blank is engaged between its right angle intersections, and the blank spread laterally to change it to the rectangular parallelogram form of the hanger without deforming or distorting the metal at the intersections. Preferably, the elongate blank is so forged that the yoke rather than the leg-forming portions lie entirely in the sides of the blank.

Referring to the drawings, an elongate hanger blank is forged from a metal bar 1, which may be cylindrical as shown in Fig. 1, and in which the fibers extend longitudinally in the manner produced by unidirectional rolling of the metal. As shown in Fig. 2, the blank has spaced substantially parallel sides connected by return-bend ends which form a part of loop-like leg-forming portions 2. Each of the sides includes a yoke-forming portion 3 intersecting at substantially right angles 4 with the leg-forming portions, the intersections 4 being of the same form as in the finished hanger. The sides of the blank are spaced as closely together as possible in order to minimize the amount of flash between them. However, enough space must be left to permit a pair of expanding tools 5 to be inserted 75 between them, and for this purpose a minimum of approximately one inch has been found to be feasible.

Each yoke-forming portion 3 is preferably larger in cross section than the remainder of the 90 blank in order to add strength where it is most needed, and, as shown in Fig. 4, is elongated so as to be pyriform or pear-shape in cross section for attachment to truck frame brackets and to brake beams in the well-known manner. 95 In the blank of Fig. 2, these yoke-forming portions are also preferably curved inwardly slightly in order to further decrease the amount of flash in the blank, and to avoid accentuated curves in the blank which cause considerable 100 distortion of the metal when they are straightened during the expanding process.

After the flash has been trimmed away and the blank heated, expanding tools 5 are placed between the yoke-forming portions, and the link 105 is stretched laterally to the rectangular form shown in Fig. 3. As the sides spread apart the leg-forming portions are drawn inwardly and straightened to form the legs 6 of the hanger, while the yoke-forming portions, if they have 110

been curved inwardly as is preferable, are pressed outwardly and straightened to form the yokes 7 of the hanger. After the blank is thus expanded, tools can then be inserted in the hanger for stretching it to more perfectly align the legs and yokes.

It will be understood that as intersections 4 are at right angles in the blank, and form the right angle corners of the finished hanger, these 10 corners are completed before the expanding operation. Therefore, when the blank is expanded its corners are not deformed and weakened, but are of uniform strength and dimension. Also, as the fibers in the blank extend longitudinally 15 thereof and follow the form of the sides of the blank as far as the ends where they emerge, transverse fibers in the finished hanger do not occur except at the center of each leg where the strain on the hanger is least.

20 In the blank described the yoke-forming portions are contained entirely within the sides of the blank, but if it be desired, the sides of the blank may comprise the leg-forming portions. This last mentioned form of blank, as shown in Fig. 6, comprises arcuate sides 16 and arcuate ends 17 having right angle intersections 14. Sides 16 and ends 17 become the parallel legs 6 and yokes 7, respectively, of the finished hanger, Fig. 3, differing in this respect from the 25 preferred form of blank whose sides and ends become the yokes and legs, respectively, of the hanger. However, it is to be noted that in the Fig. 6 form of blank the intersections 14 of the arcuate sides and ends or yokes are at right angles, and that these intersections are not deformed when the blank is expanded by tools 15 into a rectangular parallelogram. The fibers of the metal emerge at the center of each yoke, but this point, like the center of each leg, is one 30 of minimum strain. The blank may be expanded to its dotted line form by engaging it interiorly with suitable tools, as shown, and as explained with reference to the blank of Fig. 2.

According to the provisions of the patent 45 statutes, I have explained the principle of my invention and have illustrated and described what I now consider to be the best way of practicing it. However, I desire to have it understood that, within the scope of the appended 50 claims, the invention may be practiced otherwise than as specifically shown and described.

I claim:

1. The method of manufacturing a closed link 55 brake hanger of rectangular form having oppositely disposed yokes and legs, comprising forging from a bar of unidirectional rolled metal an

elongate hanger blank having spaced oppositely disposed sides, return-bend ends, and having as a part of each of said sides substantially right angle intersections of the yoke-forming with the leg-forming portions of the blank, engaging each side between its right angled intersections and spreading them laterally to straighten the portions between said intersections comprising the outwardly curved ends without deforming said corners.

80

2. The method of manufacturing a closed link brake hanger of rectangular form having oppositely disposed yokes and legs, comprising forging from a bar of unidirectional rolled metal an elongate hanger blank having spaced oppositely disposed yoke-forming sides, outwardly extending looped leg-forming ends, and having the corner intersections of the yoke and leg-forming portions at substantially right angles, engaging the yoke-forming portions of said sides and spreading them laterally to straighten said leg-forming ends without deforming said corners.

85

3. The method of manufacturing a closed link brake hanger comprising forging from a piece of uni-directional rolled steel an elongate hanger blank having arcuate hanger-forming sides and yokes intersecting each other at substantially the same angle as in the finished hanger, and expanding the blank to the form of a completed hanger without deforming said intersections.

90

4. The method of manufacturing a closed-link brake hanger of rectangular form, having oppositely disposed yokes and legs, comprising forging from a bar of uni-directional rolled metal an elongated hanger blank with sides consisting of 100 symmetrical right-angled intersecting yoke-forming and side-forming portions in which the fibres of said uni-directional bar extend transversely at the extreme ends of the blank, and engaging said sides between its right-angled intersections and spreading them laterally to straighten said leg-forming and yoke-forming portions without deforming said corners.

105

5. The method of manufacturing a brake hanger having a yoke with legs disposed at right 110 angles thereto, comprising forging a metallic body to produce an elongate hanger blank having side portions in relatively close proximity with each other and having an end portion joining the side portions, the intersections of the yoke-forming and the leg-forming portions of the blank being substantially at right angles, and stretching said blank to straighten said leg-forming portions without deforming said right angle intersections.
